[57] CLAIM

The ornamental design for a surgical rasp, substantially
as shown.

DESCRIPTION

FIG. 1 is a perspective view of the bottom of a surgical
rasp showing our new design;

FIG. 2 is a perspective view of the top of the surgical
rasp;

FIG. 3 is a side elevational view of the surgical rasp;

FIG. 4 is a top plan view of the surgical rasp; and

FIG. 5 is a cross sectional view of the surgical rasp on
the line 5—5 in FIG. 3.
